UMBRELLA

Phillip S. Sabotka, Baltimore, Md., assignor to Eichenbaum Umbrella Co., Inc., New York,
N. Y.

Application June 18, 1948, Serial No. 147,063

Term of patent 7 years

(Cl. D88—3)

To all whom it may concern:

Be it known that I, Phillip S. Sabotka, a citizen of the United States, a resident of Baltimore city, State of Maryland, have invented a new, original, and ornamental Design for an Umbrella, of which the following is a specification, reference being had to the accompanying drawing, forming a part thereof.

I claim:

The ornamental design for an umbrella, substantially as shown.

PHILLIP S. SABOTKA.
